UNITED STATES PATENT OFFICE.

EARL HOCKENBARY, OF HAMPTON, NEBRASKA.

CORN-HUSKER.

1,068,655.

Specification of Letters Patent. Patented July 29, 1913.

Application filed October 23, 1912. Serial No. 727,352.

To all whom it may concern:

Be it known that I, EARL HOCKENBARY, a citizen of the United States, residing at Hampton, in the county of Hamilton and 5 State of Nebraska, have invented certain new and useful Improvements in Corn-Huskers, of which the following is a specification.

This invention relates to corn husking implements, and pertains especially to a hand palm device of the class of twin spur corn huskers.

The object of the invention is to provide in a corn husker such novel and peculiar construction and arrangement of parts as will conveniently and comfortably conform with the shape of the hand and permit successive manipulations of the husker in husking operations without producing the usual soreness in the hand, wrist and arm.

A further object of the invention is to provide a corn husker-plate of such novel and peculiar construction and arrangement of parts as will more perfectly conform 25 with the hand-palm, and will hook or grasp a greater amount of husks so that a less number of operations is required in a single husking operation than usual, and which will permit a free and unrestricted use of 30 the hand during such operations.

In the accompanying drawings forming part of this application:—

Figure 1— is a palm view of a hand showing the applications of the invention. Fig. 35 2— is a plan view of the husker looking at the inner side thereof. Fig. 3— is an enlarged detail section taken on the dotted line $x-x$ Fig. 1. Fig. 4— is a similar view taken on the dotted line $y-y$ Fig. 1. Fig. 5— is a plan view of the palm plate, showing the lines for cutting out the husking prongs dotted. Fig. 6— is a detail perspective view of the palm-plate.

The same reference characters denote the 45 same parts throughout the several views of the drawings.

The leather wrist band 1, is provided with straps 2, and buckles 3, for attaching the band to the wrist, and a leather strip 4 is 50 riveted to the central portion of the band so as to form a plurality of rivet burs 5, for protecting the wrist band, and forming a roughened surface for the husk in a husking operation.

55 The essential feature of the invention is the metal palm plate 6, having a concaved

base 7 fitting the ball of the hand at the wrist, hand and thumb joints, and extending over such joints to cover the same. The husking prongs or hooks 8 are cut out of the plate on the dotted lines $a-a$, Fig. 5, so as to leave a central stem 9 for connecting the plate head 10 with the base 7, of the plate. The stem and the head constitute a T-shaped plate portion of the palm plate 60 and said stem tapers from the head to the base of the palm plate. The stem 9 is concaved lengthwise to conform with the shape of the palm of the hand. One end of the T-head is longer than the other, and such 65 longer end has a compound curve for the purpose of having the inner edge of this end raised outwardly from the hand-palm and the outer edge of said end extends inwardly, so as to closely conform to and fit 70 the joint between the thumb and the hand. The prongs 8 are bent backward and overhang the base portion of the plate at each edge of the T-stem so as to leave a space between the prongs of greater width than the 75 width of the prongs or the width of the stem 9 at the base 7, for the purpose and advantage of having the prongs hook a greater area of husk than usual in a single 80 hooking operation and to permit the husked portion of the corn to occupy the space 85 between the prongs. The prongs 8 have curved or convexed edges tapering into a rounded point so that there are no sharp 90 edges or points to injure or mutilate the corn during a husking operation.

A hand strap 11 is attached to the inner side of the T-head by rivets forming a pair of burs 12 on each end of said head, and said burs assist in holding and preventing 95 the husk from slipping and in grasping it with the fingers in a husking operation. A leather palm pad 13, is attached to the wrist band by means of the rivets 5, and extends under the palm plate, and is connected with the T-head by the strap 11 extending through slots 14 in the corners of the pad 13, so that the pad may adjust itself to the palm of the hand and to the shape of the palm plate. The T-head is inclined at 105 an angle to the stem 9 and to the prongs 8 so as to follow the knuckle-joint line in the palm of the hand, and thereby permit free and unrestricted movement of such joints.

110 It will be observed that owing to the peculiar shape of the palm plate, the husk

is more readily grasped by the prongs; that the fingers of the hand, being separated only by the T stem, have greater grasping space than usual; that, by reason of the long 5 twisted or curved shape of one end of the T-head such end fits under the joint between the hand and the thumb so as not to interfere with the action of such joint, and that the other a short end of the T-head may be 10 located on the ball of the palm and back of the said joint line.

I do not wish to confine or restrict myself to any particular size or material, in the manufacture of the invention, but reserve 15 the right to make such changes therein as may come within the scope of the appended claims.

Having thus described my invention what I claim as new and desire to secure by Letters Patent is:—

20 1. In a corn husker, the combination with a wrist band, a palm strap, and a palm pad, of a husking plate having a T-shaped portion formed therein, a husking prong struck from the plate on each side edge of the stem of the head and overhanging the base 25 of the plate at the intersection of the stem and the base, and means for securing the plate to the wrist band.

25 2. In a corn husker, the combination with a wrist band, a palm strap, and a palm pad, of a husking plate having a T-shaped portion formed therein, a husking prong struck from the plate on each side edge of the stem 30 of the head and overhanging the base of the plate at the intersection of the stem and the base, a palm strap attached to the T-head and extending through the palm pad, and means for securing the pad and the 35 wrist band to the base of the plate.

40 3. A corn husking plate comprising a T-

shaped portion having a tapered stem and a head inclined at an angle to the stem, a pair of husking prongs struck up from the plate and separated by the stem at the 45 intersection of the stem and the base of the plate and overhanging said base.

4. A one piece corn husking plate comprising a base portion, a T-shaped portion projected from the base and having an inclined twisted head one end of which is longer than the other, and a pair of husking prongs struck out of the plate between the head and the base and overhanging said base portion.

5. In a husking device, a wrist band having attaching means and a husking element connected with the wrist band adjacent to the upper edge thereof, said husking element comprising a base plate having an upwardly extending shank provided with an obliquely disposed cross-bar, one arm of which, extending in the direction of the thumb of the operator, projects materially beyond the corresponding side edge of the 60 base plate, and the lower edges of the arms of the cross-bar being curved to merge with the side edges of the shank, thereby presenting arcuate recesses, said base plate being provided with downturned sharp pointed 65 prongs formed of the material originally lying adjacent to the side edges of the shank and spaced apart thereby; and an attaching strap secured upon the underside of the 70 cross-bar.

75 In testimony whereof I affix my signature in presence of two witnesses.

EARL HOCKENBARY.
